No. 893,329.

PATENTED JULY 14, 1908.

F. KLOSINSKI.
CAN LOCK AND COVER.
APPLICATION FILED APR. 4, 1908.

UNITED STATES PATENT OFFICE.

FRANK KLOSINSKI, OF ST. LOUIS, MISSOURI.

CAN LOCK AND COVER.

No. 893,329.

Specification of Letters Patent.

Patented July 14, 1908.

Application filed April 4, 1908. Serial No. 425,230.

To all whom it may concern:

Be it known that I, FRANK KLOSINSKI, a subject of the Czar of Russia, residing at St. Louis, in the State of Missouri, have invented 5 a new and useful Can Lock and Cover, of which the following is a specification.

This invention relates to closures for milk-cans and similar containing vessels and has for its object to provide a comparatively simple and inexpensive device of this character which forms an air and liquid tight cover for the vessel so as to effectually prevent the contents thereof from spilling or leaking at the cover during transportation or shipment.

15 A further object of the invention is to provide improved means for locking the cover in engagement with the can, and means for limiting the swinging movement of the pivoted locking bail.

20 A still further object of the invention is generally to improve this class of devices so as to increase their utility, durability and efficiency as well as to reduce the cost of manufacture.

25 Further objects and advantages will appear in the following description, it being understood that various changes in form, proportions and minor details of construction may be resorted to within the scope of the 30 appended claims.

In the accompanying drawings forming a part of this specification: Figure 1 is a side elevation of a containing vessel provided with a combined cover and lock constructed 35 in accordance with my invention, the pivoted locking bail being shown in lowered or operative position. Fig. 2 is a similar view of the same showing the locking bail in released position. Fig. 3 is a front elevation, 40 the cover being shown in elevated position to expose the contents of the vessel. Fig. 4 is a detail transverse sectional view of the cover and its associated parts.

Similar numerals of reference indicate corresponding parts in all of the figures of the drawings.

The improved device forming the subject matter of the present invention may be used in connection with milk cans and similar containing vessels and by way of illustration is shown in connection with a milk can of the ordinary construction in which 5 designates the body of the can and 6 the neck, preferably reinforced and strengthened by a ring or 55 band 7, as shown.

The cover 8 is provided on its lower face with an annular groove 9 in which is seated a gasket 10 which bears against a reinforcing rib 11 formed on the upper end of the neck 6 and serves to form an air and liquid tight 60 joint between the can and closure.

Secured to the top of the cover 8 is a handle 12, preferably formed from a metal rod, the intermediate portion of which is bowed outwardly and the opposite ends thereof extended through suitable loops or clips 13 fastened to the top of the cover 8 to produce laterally extending lugs 14.

Secured to the reinforcing band 7 are oppositely disposed ears 15 the free ends of which 70 are extended vertically above the top of the can and are bifurcated to form terminal sockets 16 adapted to receive the locking lugs 14.

Extending laterally from the band 7 are 75 trunnions 17 on which is pivotally mounted for swinging movement a locking bail or yoke 18, the latter being retained in position on the trunnions by cotter pins or similar fastening devices 19.

The bail or yoke 18 is provided with a cam face 20 which bears against the lugs 14 and forces the latter within the socket 16 when the bail is swung downwardly to operative position thereby to clamp the cover in engagement with the neck of the can.

The closed end of the yoke 18 is bent laterally to form a loop 21 which registers with an arm 22 secured to and extending at right angles to the band 7, said arm being provided with a slot 23 so as to permit the insertion of the shank of a pad-lock or similar fastening device 24.

The opposite arms of the locking bail or yoke are spaced from the ears 15 by circular 95 blocks or washers 24', while the terminals of the arms at the trunnions 17 are provided with extensions 25 having inclined faces 26 which bear against the correspondingly inclined faces of suitable lugs or enlargements 100 27 secured to the reinforcing band 7, thereby to limit the swinging movement of the locking bail or yoke.

The cover 8 is preferably combined with the can by a chain or similar flexible medium 105 28 so as to prevent accidental displacement of the cover when the latter is moved to open position.

In sealing the can the cover or closure 8 is placed in position on the bead 11 with the 110

- lugs 14 seated in the sockets 16 of the ears 15 after which the operator grasps the locking bail by the loop 21 and moves the latter to the position shown in Fig. 1 of the drawings.
- 5 As the locking bail or loop is swung to operative position on the trunnions 17 the can faces 20 will engage the lugs 14 and force said lugs within the sockets 16 thus compressing the gasket 10 and forming an air and liquid tight joint between the parts. After the bail has been moved to operative position the shank of the pad-lock is extended through the loop 21 and the slot 23 so as to effectually prevent an unauthorized person 10 from obtaining access to the contents of the can.

In order to open the can it is merely necessary to remove the lock 24 and then swing the locking bail laterally to the position 20 shown in Fig. 2 of the drawings thus permitting the cover to be detached from the can by exerting an upward pull on the operating handle 12. It will thus be seen that the loop 21 not only serves as a means for engagement 25 with the pad-lock but also forms an operating handle by means of which the bail may be moved to operative and inoperative position. If desired, however, the lock may be dispensed with, the can face 20 being relied 30 upon to lock the lugs 14 within the sockets of the supporting ears.

The improved mechanism herein shown and described may be applied to milk cans or other containing vessels of different sizes and 35 shapes and if desired, the reinforcing band of the can may be dispensed with and the locking bail or yoke and its associated parts attached directly to the exterior walls of the vessel.

40 From the foregoing description it will be seen that there is provided an extremely simple, inexpensive and efficient device admirably adapted for the attainment of the ends in view.

45 Having thus described the invention what is claimed is:

1. The combination with a containing vessel having vertically disposed ears the free ends of which are bifurcated to form 50 terminal sockets, of a cover extending transversely across and bearing against the top of the receptacle and having a rod secured thereto, the intermediate portion of which is bowed laterally to form a handle and the 55 opposite ends thereof extended to form lugs adapted to engage the sockets, a slotted arm secured to and disposed at right angles to the vessel, and a locking bail pivotally mounted on the vessel and having one end 60 thereof bent laterally to form a movable

locking member adapted to register with the slot in the arm for the reception of a locking device, said bail being provided with a cam face adapted to engage the lugs when the bail is moved to operative position.

65

2. The combination with a containing vessel having enlargements formed thereon and provided with inclined faces, of a cover extending transversely across and bearing against the top of the vessel and provided with laterally extending lugs, ears secured to the vessel at said enlargements and having their upper ends extended above the top of the vessel and bifurcated to form sockets for the reception of the lugs, a locking bail pivotally mounted on the vessel and having its pivoted ends provided with extensions formed with inclined faces adapted to engage the inclined faces of the enlargements, said bail being provided with cam faces adapted to engage the lugs when the bail is moved to operative position.

3. The combination with a containing vessel having a reinforcing band secured thereto, of a cover extending transversely across the top of the vessel and having its lower face provided with an annular seating groove, a gasket seated in said groove, clips secured to the upper face of the cover, a rod journaled in the clips and having its opposite ends extended beyond the peripheral edge of the cover to form lugs, the portion of the rod between the clips being bowed laterally to form an operating handle, vertically disposed ears secured to the reinforcing band and having their upper ends bifurcated to form sockets for the reception of the ears, trunnions extending laterally from the reinforcing band, a locking bail pivotally mounted on the trunnions and having a cam face adapted to engage the lugs when the bail is moved to operative position, enlargements formed on the reinforcing band and provided with inclined faces, a slotted arm extended laterally from the reinforcing band, extensions formed on the pivoted ends of the yoke and having their ends inclined for engagement with the inclined faces of the adjacent enlargements, the closed end of the yoke being bent laterally to form a loop adapted to register with the slot in the arm for the reception of a locking device.

In testimony that I claim the foregoing as my own, I have hereto affixed my signature in the presence of two witnesses.

FRANK KLOSINSKI.
